UNITED STATES PATENT OFFICE

128,639

DESIGN FOR A MINIATURE ARTIFICIAL CHRISTMAS TREE

Wilhelm Hans Nietsche, Williamsburg, Mass.

Application April 8, 1941, Serial No. 100,231

Term of patent 3½ years

To all whom it may concern:

Be it known that I, Wilhelm Hans Nietsche, a citizen of the United States, residing at Williamsburg, in the county of Hampden and State of Massachusetts, have invented a new, original, and ornamental Design for a Miniature Artificial Christmas Tree, of which the following is a specification, reference being had to the accompanying drawing, forming part thereof.

Fig. 1 is a front elevational view of a miniature artificial Christmas tree showing my new design, and

Fig. 2 is a side elevational view of the Christmas tree shown in Fig. 1.

The essential features of my design resides in the specific configuration of the main body portion of the tree and the particular spaced stepped arrangement thereon of the lights, all as shown in the drawing.

I claim:

The ornamental design for a miniature artificial Christmas tree, as shown and described.

WILHELM HANS NIETSCHE.
